CLAIM

The ornamental design for an electronic device, as shown and described.

DESCRIPTION

FIG. 1 is a top front perspective view of an electronic device showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof;

FIG. 8 is a bottom rear perspective view thereof;

FIG. 9 is an enlarged view of the delineated portion 9 in FIG. 3;

FIG. 10 is an enlarged view of the delineated portion 10 in FIG. 5; and,

FIG. 11 is an enlarged view of the delineated portion 11 in FIG. 8.

The dashed broken lines in the figures depict portions of the electronic device that form no part of the claimed design.

The dot-dash broken lines in the figures define the boundaries of the claimed design and form no part thereof.

The dot-dot-dash broken lines in the figures delineating portions of the claimed design that are illustrated in enlargements form no part of the claimed design.

1 Claim, 11 Drawing Sheets
